UNITED STATES PATENT OFFICE

GEORGE R. INGHAM, OF AJO, ARIZONA

STEAM SHOVEL SAFETY ATTACHMENT

Application filed July 23, 1929. Serial No. 380,313.

The present invention relates to a safety attachment for steam shovels to protect the workmen from injury by chains breaking during the operation of the shovel.

5 An important object of the invention resides in the provision of an attachment of this nature which is exceedingly simple in construction, inexpensive to manufacture, easy to install, thoroughly efficient and reliable in use, and otherwise well adapted to the purpose for which it is designed.

With the above and numerous other objects in view as will appear as the description proceeds, the invention resides in certain novel 15 features of construction, and in the combination and arrangement of parts as will be hereinafter more fully described and claimed.

In the drawings:

Figure 1 is a fragmentary side elevation 20 of a steam shovel showing my improved attachment mounted thereon,

Figure 2 is a perspective view of the chain guard,

Figure 3 is an end elevation of the chain 25 guide, and

Figure 4 is a side elevation thereof.

Referring to the drawings in detail it will be seen that the chain guard is denoted generally by the numeral 8 and comprises a vertical section *a* with an obliquely inclined extension *b*. This chain guard 8 is of channel formation and is adapted to be bolted, riveted or otherwise fastened as at 14 to sheave supports 13.

30 The extension *b* is attached to the sheave supports by suitable fastening means through plates *c*.

The chain guide is denoted generally by the numeral 9 and comprises a tubular body 40 flared outwardly at its forward end. This tubular body formed of an upper section *d* and a lower section *e*. These sections are fastened together by means of bolts 30 through openings in angle iron 31 permanently riveted to the meeting edges of the sections *d* and *e*.

The chain guide is fastened to the boom engine 16 by suitable bolts passing through openings 18 and 18' formed in arms 19 and 50 20 respectively which are fastened to the

section *e* in any suitable manner and a brace rod 21 is fastened to these arms 19 and 20 to extend diagonally therebetween.

In normal operation the dipper 1 is raised by chain 2 that runs over sheaves 3, 4 and 5 and also block 6 and is wound on some suitable mechanism (not shown) situated inside the cab 7.

55 The chain 2 breaks occasionally for obvious reasons, such as too heavy a load on the dipper 1. When the chain guard 8 and the chain guide 9 are not installed and the chain 2 breaks at any place at the right of sheave 3, the loose end will flop over sheave 3 and is liable to strike either the dipper operator who is seated on stool 10 or the shovel operator who is seated on the stool 11, causing them 60 injury.

65 When the chain guard 8 is installed and the chain 2 breaks at any place between the sheave 3 and point 12, the loose end is prevented from striking either the operator by the chain guard 8 but if the chain 2 breaks at point 12 or beyond, the loose end is apt to flop back or over the chain guard 9 and hit either 70 operator before the same has time to go through the chain guard 8.

75 When both the chain guard 8 and the chain guide 9 are installed and the chain breaks at any point beyond 12, the loose end is prevented from flopping back and striking either operator, as the chain 2 guides the loose end of the chain through the chain guard 8 and will not let it flop over the chain guard 8. The chain guard 8 should be constructed of heavy 80 material that will absorb the heavy impact when the broken chain strikes it. The chain guard 8 can readily be taken off by removing bolt 14 so that the sheave 3 can be removed or repaired.

85 The chain guard 9 is also made of heavy material to stand the sudden impact in case the broken chains hit it.

90 It is thought that the construction, utility and advantages of this invention will now be quite apparent to those skilled in this art without a more detailed description thereof.

95 The present embodiment of the invention has been disclosed in considerable detail merely for the purposes of exemplification

since in actual practice it attains the features of advantage enumerated as desirable in the statement of the invention and the above description.

5 It will be apparent that changes in the details of construction, and in the combination and arrangement of parts may be resorted to without departing from the spirit or scope of the invention as hereinafter claimed or sacrificing any of its advantages.

10 Having thus described my invention, what I claim as new is:

15 In a steam shovel, the combination with the boom, sheaves at the ends of the boom, and a hoist chain passing over said sheaves, of a pair of relatively spaced chain guards, one of said guards being of elongated channel section and fastened to a lower sheave support and of substantially L-shape for cov-
20 ering the inner side of the sheave and lower portion of the hoist chain and the other guard consisting of a relatively short tube fastened to the boom in spaced relation to the lower sheave support and encircling the portion of the hoist chain immediately above the lower sheave, said tubular guard being flanged outwardly at its upper end.

25 In testimony whereof I affix my signature.

GEORGE R. INGHAM.
